UNITED STATES PATENT OFFICE.

JOHN F. BERGEN AND JACOB MARCUS, OF BROOKLYN, NEW YORK.

BINDER ATTACHMENT FOR SEWING-MACHINES.

1,397,853.

Specification of Letters Patent.

Patented Nov. 22, 1921.

Application filed March 4, 1920. Serial No. 363,259.

To all whom it may concern:

Be it known that we, JOHN F. BERGEN, a citizen of the Republic of Lithuania, residing in Brooklyn, in the county of Kings and State of New York, and JACOB MARCUS, a citizen of the Republic of Poland, residing in Brooklyn, in the county of Kings and State of New York, have invented certain new and useful Improvements in Binder Attachments for Sewing-Machines, of which the following is a specification.

This invention relates to improvements in binders of the type usually designated as combination right angle binders, by means of which the strip of material is folded and fed in a direction at right angles to its initial direction of feed, and in which the raw edges of the binding strip will also be folded over in readiness to be stitched to the material to be faced or bound, whereby the necessity of first preparing the binding strip with its edges turned and pressed down is avoided.

An object of the invention is the provision of an improved binder of the character described, simple in construction, inexpensive to manufacture and effective and durable in use to accomplish the purposes set forth.

Other objects of the invention are to simplify the construction of the binder and to provide a removable guide-tongue for facilitating the starting of the binding strip, and simplifying the construction of the device and making more economical its manufacture.

Other objects of the invention will appear as the description proceeds, and while herein minute details of the invention are disclosed, the invention is not limited to these, since many and various changes may be made without departing from the scope of the invention as claimed.

In the accompanying drawings showing by way of example one of many possible embodiments, of the invention,

Figure 1 is a front elevation of the binder. Fig. 2 is a bottom view;

Fig. 3 is an end view;

Fig. 4 shows a section taken on the line 4-4 of Fig. 2, parts being omitted;

Fig. 5 is a perspective view of the tongue, the front face thereof being shown uppermost;

Fig. 6 is a perspective view of the tongue showing the rear face thereof uppermost;

Fig. 7 is a perspective view of the main folding plate of the binder and its support,

the open front face being shown uppermost, the guide-tongue being removed;

Fig. 8 shows a section on the line 8-8 of Fig. 1, and Fig. 9 is a fragmental perspective view of the delivery end of the folding plate.

A base plate 10 (shown in bottom plan in Fig. 2) is mounted on the machine bed and formed with an upright bracket plate 11 on its front edge. A folding plate 12 is secured on the forward face of said bracket plate 11 approximately in the plane thereof and formed at its receiving end with a substantially flat rearwardly beveled receiving face 14 (Fig. 7) substantially the width of the binding strip 15, (Figs. 1 and 2). The front face of said folding plate is formed with an axial rib 16, highest and narrowest and deeply notched, as at 17, (Fig. 9) at its delivery end, and gradually merging into said receiving face 14. Said plate 12 is also formed with converging side flanges 18 extending from end to end of the side edges of the folding plate and co-operating with said rib to form grooves or troughs 20 (Fig. 4). Said plate 12 is provided near its ends with inwardly and rearwardly folded delivery-end lips 21 (Fig. 7) and receiving-end lips 22 extending to near the ribs 16, the receiving-end lips 22 being bent to be nested in and slightly spaced from said troughs 20.

Wire-end loops 25 (Figs. 7 and 9) are provided on the delivery end of said flanges thereby to form inwardly projecting edges 90 for the delivery end of the flanges.

A friction guide-tongue 27 (Fig. 5) frontwardly beveled at the receiving end as at 28 and deeply notched as at 29 at the delivery end is disposed within the folding plate (Fig. 1) conforming approximately to the shape of said rib 16 and contacted by and held near said rib by said lips 21 and 22. Said tongue is axially slotted to provide a start-feed slot 30 for starting the feeding of 100 the binding strip.

Said tongue is provided at its receiving end with outwardly, backwardly and inwardly curved side wings 32 (Figs. 5 and 6) received between said flanges 18 and under 105 the receiving-end lips 22 to form with said flat face 14 an approximately rectangular vertical throat 33 (Fig. 8) merging into an approximately W-shaped passage at said receiving-end lips 22.

Before starting the feeding of the strip, the tongue 27 is removed by drawing it out

from under the lips 21 and 22. The end of the strip is then placed in the folding plate, and the tongue replaced. A pin or the like may be thrust through the slot 30 to force the strip along until it is in position to feed properly.

In the operation, the binding strip 15, with its raw edges, is passed in the direction of the arrow of Fig. 1, into the throat 33 at the 10 delivery end thereof, whereupon the strip is convexed frontwardly centrally of its width by reason of the frontwardly curved rib 16. At the same time the edges of the strip are turned up by the flanges 18 as the 15 latter converge. As the strip further passes into the folding plate, the strip receives a W-shaped cross section, the raw edges of the strip contacting the lips 21, the rib 16 holding up the middle of the strip, while the 20 part about half way between the middle and the edges is held down by the side edges of the tongue 27. When the strip reaches the delivery end of the folding plate it passes rearwardly through the notch 17 and 25 is turned outside-in or reversed and simultaneously guided or fed in a direction at substantially a right angle to its initial direction of feed, so that the folded-in edges of the strip are brought in opposition to 30 each other and in position to be sewed upon the top and bottom of the work 35 (Fig. 2), which is fed across the bed plate of the machine in the direction of the arrow of Fig. 2, in the usual manner, the usual feeding 35 mechanism of the machine drawing the work, together with the facing or binding strip 15 under the presser foot in the usual manner.

The binding strip 15 is, during its movement in one direction, folded with its raw edges turned over away from each other, but that subsequently the binding strip is turned outside-in to bring these folded-in edges opposed to each other, one above the other, 45 with the strip in position to be folded over the edge of the work 35 with one side thereof on top of the work and the other underneath thereof, so that the necessity of first folding the edges of the strip before feeding 50 the same to the folder is done away with.

We claim:

1. In combination, a folding plate; and a removable guide member free of attachment to other structure and constructed and 55 positioned to be loosely held on said plate in operative holding position by material passing between the plate and guide member.

2. In combination, a folding plate; and a removable guide member free of attachment 60 to other structure and constructed and positioned to be loosely held on said plate and yieldably pressed in the direction of the feed in holding position by material passing between said plate and guide member.

3. In combination, a pair of associated

guiding parts one of which is free of attachment to other structure and freely movable toward its receiving end and constructed and positioned to be yieldably held against such movement by the action of material operated 70 upon thereby.

4. In combination, a folding plate; a removable guide member thereon in partial spaced relation thereto and movable toward the receiving end of said plate; said guide 75 member being free of attachment with other structure.

5. In combination, a fixed holding plate; a removable guide member thereon in partial spaced relation thereto and freely movable 80 toward the receiving end of said plate and constructed and positioned to be yieldably held against such movement by the action of material operated upon thereby; said guide member being free of attachment with 85 other structure.

6. In combination, a fixed folding plate; a removable guide member held thereon in partial spaced relation thereto and against 90 up and down and lateral movement thereon and freely movable toward the receiving end of said plate and constructed and positioned to be yieldably held against such movement by the action of material operated upon thereby; said guide member being free of 95 attachment with other structure.

7. In combination, a folding plate formed with a receiving front-face at the receiving end, an axial rib merging into said face and side flanges coöperating with said rib to 100 form troughs; and a guide tongue conforming approximately to the shape of said rib and held near said rib, and provided with outwardly and backwardly curved wings between said side flanges.

8. In combination, a folding plate formed with a receiving front-face at the receiving end, an axial rib merging into said face, and side flanges coöperating with said rib to 110 form troughs; and a guide tongue conforming approximately to the shape of said rib and held near said rib, and provided with outwardly and backwardly curved wings between said side flanges forming with said receiving face a wide throat merging into a 115 passage of approximately W-shaped cross-section.

9. In combination, a folding plate formed with a flat receiving face, an axial rib merging into said face, and side flanges provided 120 with inwardly folded lips extending to near the rib; and a guide-tongue conforming to the shape of the rib and held near thereto by said lips.

10. In combination, a folding plate formed 125 with a receiving face, an axial rib merging into said face, and side flanges forming grooves and provided with inwardly and backwardly folded receiving-end lips extending to near the ribs and nested in and 130

slightly spaced from said groove; and a guide-tongue conforming to the shape of the rib and held near thereto by said lips and provided with outwardly, backwardly, 5 and inwardly curved side wings at its receiving end adapted to be received between said flanges and under the receiving-end lips.

11. In combination, a folding plate formed with a receiving face, an axial rib 10 merging into said face, and side flanges forming grooves and provided with inwardly and backwardly folded delivery end lips and receiving-end lips, the receiving-end lips being nested in and slightly spaced 15 from said grooves; and a guide-tongue conforming to the shape of the rib and held near thereto by said lips and provided with side wings at its receiving end adapted to be received between said flanges and under 20 the receiving-end lips.

12. In combination, a folding plate formed with a flat receiving face; an axial rib merging into said face, and side flanges 25 forming grooves therewith and provided with inwardly and backwardly folded delivery end lips and receiving-end lips extending to near the ribs, the receiving-end lips being nested in and slightly spaced from said grooves; and a guide tongue 30 conforming to the shape of said rib and held near thereto by said lips and provided with outwardly, backwardly and inwardly curved side wings at its receiving end adapted to be received between said flanges and under 35 the receiving-end lips to form with said flat face an approximately rectangular vertical throat merging into an approximately W-shaped passage at said receiving-end lips.

13. In combination, a folding plate with 40 a flat receiving front-face at the receiving end, an axial rib deeply notched at its delivery end and merging into said face, and side flanges coöperating with said rib to form troughs; and a guide-tongue conforming 45 approximately to the shape of said rib and held near said rib, and provided with outwardly and backwardly curved wings between said side flanges forming with said flat face a wide throat merging into a passage 50 of approximately W-shaped cross-section.

14. In combination, a folding plate formed with a substantially flat receiving front-face at the receiving end, an axial rib, highest and narrowest and deeply notched 55 at its delivery end, and merging into said receiving face, and side flanges coöperating with said rib to form a pair of tapering converging troughs increasing in depth and 60 decreasing in width toward the delivery end; holding lips on said flange and extending to near the rib and nested in and slightly spaced from the walls and floor of said troughs; and a guide-tongue conforming 65 approximately to the shape of said rib

and held near said rib by said lips and having its side edges deep in said troughs, the receiving end of the tongue being provided with outwardly, backwardly and inwardly curved wings received between said side flanges and under the lips to form, with said flat face, an approximately rectangular vertical throat merging into a passage of approximately W-shaped cross-section at 70 said lips.

15. In combination, an upright bracket plate, a folding plate secured on the front of said bracket plate and formed with a substantially flat receiving front-face, with an axial rib, highest and narrowest and deeply notched at its delivery end, and gradually merging into said receiving face, and with side flanges coöperating with said rib to 75 form a pair of tapering converging troughs increasing in depth and decreasing in width 80 toward the delivery end of the folding plate; delivery-end lips and receiving-end lips on said flange and extending to near the rib, the receiving-end lips being nested in and slightly spaced from said troughs; and a 85 guide-tongue conforming approximately to the shape of said rib and adapted to be held near said rib by said lips and having its side edges deep in said troughs the receiving end of the tongue being provided 90 with outwardly, backwardly and inwardly curved wings received between said side flanges and under the receiving-end lips to form, with said flat face, an approximately 95 rectangular vertical throat merging into a 100 passage of approximately W-shaped cross-section at said receiving-end lips.

16. In combination, an upright bracket plate, a folding plate secured on the front of said bracket plate and formed with a substantially flat receiving front face, with an axial rib, highest and narrowest and deeply notched at its delivery end, and gradually merging into said receiving face, and with side flanges coöperating with said 105 rib to form grooves and extending from end to end of the folding plate and provided near its end with inwardly and rearwardly folded delivery-end lips and receiving-end lips extending to near the rib, the receiving-end lips being nested in and slightly spaced 110 from said grooves; and a friction guide-tongue deeply notched at the delivery end and conforming approximately to the shape of said rib and adapted to be held near said 115 rib by said lips and provided with forwardly, backwardly and inwardly curved wings at its receiving end adapted to be received between said side flanges and under the receiving-end lips to form, with said 120 flat face, a vertical throat.

17. In combination, an upright bracket plate; a folding plate secured on the front of said bracket plate and formed with a substantially flat receiving front face, with 125

- an axial rib, highest and narrowst and deeply notched at its delivery end, and, gradually merging into said receiving face, and with side flanges coöperating with said 30
5 rib to form grooves and extending from end to end of the folding plate and provided near its ends with inwardly and rearwardly folded delivery-end lips and receiving-end 35
10 lips extending to near the rib, the receiving-end lips being nested in and slightly spaced from said grooves; wire-end loops provided on the delivery end of said side flanges and spaced nearer together than said flanges thereby to form inwardly projecting edges; 40
15 and a friction guide-tongue deeply notched at the delivery end and conforming approximately to the shape of said rib and adapted to be held near said rib by said lips and provided with forwardly, backwardly and 45
20 inwardly curved wings at its receiving-end adapted to be received between said side flanges and under the receiving-end lips to form, with said flat face, a vertical throat.
18. In combination, a folding plate, the front face thereof formed with a receiving face at the receiving end, an axial rib, deeply notched at its delivery end, and gradually merging into said receiving face, and with side flanges coöperating with said 50
- rib to form grooves and extending from end to end of the side edges of the folding plate and provided near its ends with inwardly folded lips extending to near the rib; and a removable friction guide-tongue conforming approximately to the shape of said rib and adapted to be contacted by and held near said rib by said lips.
19. In combination, an upright bracket plate; a folding plate, the front face thereof formed with a receiving face at the receiving end, an axial rib, highest and narrowst and deeply notched at its delivery end, and gradually merging into said receiving face, and with side flanges coöperating with said rib to form grooves and 40
extending from end to end of the side edges of the folding plate and provided near its ends with inwardly folded lips extending to near the rib; and a removable friction guide-tongue conforming approximately to the shape of said rib and adapted to be contacted by and held near said rib by said lips.
